METHOD AND APPARATUS FOR CONTINUOUS COUNTER-CURRENT SOLVENT EXTRACTION OF SOLID MATERIALS

Michele Bonotto, Evansville, Ind., assignor to Extractol Process, Ltd., Wilmington, Del., a corporation of Delaware

Application December 13, 1937, Serial No. 179,458

7 Claims. (Cl. 260—412.8)

This invention relates to a method and apparatus for continuous counter-current solvent extraction of solid materials and though useful generally, is particularly adapted for the extraction of fats and oils from products of such nature or qualities that the extracted material will be incapable of forming or in which difficulty is experienced in forming, at the discharge end of an extraction unit, a liquid-impervious plug of sufficient density to hold back the solvent liquid during discharge of the exhausted material at atmospheric pressure.

One of the objects of this invention is to provide a method and means whereby extracted material of the type hereinabove specified from an extraction unit may be sufficiently compressed under pressures equalized on both sides of the compressed zone to block passage therethrough of the solvent supply and permit a counter-flow of solvent in the extraction unit.

Another object of my invention is, in a passage, conduit or chamber communicating with an extraction unit and having equalized hydrostatic pressure on opposite sides thereof, to compress a mass of extracted material to a density which will provide greater impenetrability and resistance to the passage of liquid than will be encountered in the counter-flow of supply solvent through the solid material being extracted in the extractor unit.

Another object of my invention is, in an extraction system where raw material is fed at one end, exhausted material is discharged through a unit outlet at the opposite end, and solvent is passed in counter-current therethrough, to provide means for equalizing the hydrostatic pressure at opposite sides of the discharge outlet, means for compressing exhausted material adjacent to said discharge end and means for by-passing a supply of fresh solvent around the discharge outlet while maintaining such equalized hydrostatic pressure at opposite sides of the discharge outlet.

Still another object of my invention is, in an apparatus of the character specified, to utilize, in combination with a column of liquid solvent connected with the discharge end of an extracting unit to equalize the hydrostatic pressure therein, a solvent by-pass from such solvent column, a supply pump of given capacity for feeding solvent to said solvent column, and a by-pass pump of a capacity substantially equal to the capacity of the supply pump, whereby the equalizing pressure of said solvent column will be maintained at the discharge side of the discharge conduit and the feed of the solvent to the system and the input

of solvent to the extraction unit through the bypass will be substantially equal in quantity.

Another object of my invention is to provide for material discharged from an extraction unit an elevating conveyor having ascending and descending legs and to utilize one of such legs as a material conveying leg for exhausted material while employing the other leg to provide a column of solvent of suitable hydrostatic pressure.

Still another object of my invention comprises the provision, in a conveyor of the character specified, of means for washing the exhausted material with fresh solvent by causing such solvent to percolate in counter-current through such exhausted material during elevation of the same to the conveyor discharge outlet and preferably adjacent to said outlet.

Another object of my invention is, in a conveyor device of the type specified, to provide for the drainage from ascending exhausted material soaked during the aforesaid percolation of solvent and the conduction of such drained solvent to the pressure-equalizing solvent column.

With these and other objects in view, the invention comprises the combination of members and arrangement of parts so combined as to coact and co-operate with each other in the performance of the functions and the accomplishment of the results herein contemplated, and comprises in one of its adaptations the species or preferred form illustrated in the accompanying drawings, in which:

Fig. 1 is a view partly schematic and partly in vertical section showing an apparatus capable of carrying out my invention;

Fig. 2 is a cross-section on the line 2—2 of Fig. 1, looking in the direction of the arrows;

Fig. 3 is a cross-section on the line 3—3 of Fig. 1, looking in the direction of the arrows;

Fig. 4 is an enlarged fragmentary sectional view of a part of one of the revolving partition discs and the stationary arm shown in Fig. 1;

Fig. 5 is an enlarged fragmentary section of the upper part of my conveyor;

Fig. 6 illustrates a modified form of conveyor apparatus capable of use in my invention;

Fig. 7 is a view partly schematic, partly in vertical section and partly in elevation showing a modified form of my apparatus;

Fig. 8 is a fragmentary sectional view of another form of my apparatus similar to Fig. 7 but slightly modified;

Fig. 9 is a view partly schematic, partly in sec-

tion and partly in elevation showing still another modified form of my apparatus; and

Fig. 10 is a section on the line 10—10 of Fig. 8, looking in the direction of the arrows.

Referring now to Figs. 1 to 5 of these drawings which illustrate a preferred embodiment of my invention, I indicates an extraction unit of a type similar to that disclosed in my co-pending patent application Serial No. 48,646, and comprises, as shown, a vertically arranged cylindrical tank having, at its upper end, an inlet 2 for solid material from which oil, fat or the like is to be extracted. As shown, the solid material is fed from a storage bin 3 by means of a feed screw 4 operating in a feed conduit 4'. The solid material is distributed by a distributing plate 5 and passed by gravity through a series of successive superposed extraction zones 6 separated from each other by revolving discs 7 each having a radial opening 8 disposed out of registration with preceding and succeeding openings, and each zone preferably being provided with stationary vertically-disposed radially-extending arms 9 adapted to hold the solid material against turning with the revolving discs 7. The tank 1 has, at its lower end, an inlet 10 for solvent and the solid material and solvent are caused to move in counter-current with each other through the openings 8 in the revolving discs 7 which are provided at their perimetric edges with inset expansion rings 8' which rub and bear against the internal surface of the tank so as to provide a substantially liquid-tight joint between zones and to compel the liquid solvent material to pass through the openings 8 in the revolving discs in counter-current with the movement of the raw solid material. During such counter-current movement, the oil, fat or like soluble contents will be extracted from such raw material, and the exhausted material will be discharged at or adjacent to the bottom of the tank while the miscella will be discharged at or adjacent to the top of the tank. In the embodiment shown, the partition members or discs 7 are rotated by an axial shaft 11 rotatable by bevel gears 11', 11", the latter of which is fixed on a shaft 12 turned by a motor 13.

My present method and apparatus, though capable of general use with all types of material, is particularly adapted for use with raw material such as scrap meat which, in its exhausted form, does not provide sufficient body or texture to permit or enable the formation, at the discharge end of the extraction unit, of a liquid-impervious plug which will have sufficient density to withstand or hold back the hydrostatic pressure within the extraction unit while discharging exhausted material at atmospheric pressure. To overcome this difficulty, I substantially equalize the hydrostatic pressure on opposite sides of the discharge conduit of an extraction unit by providing a column of solvent connected with the discharge end of such conduit and I then bypass, around such discharge conduit, a supply of solvent and compress such exhausted material in a zone adjacent to the discharge outlet to produce a compressed mass having a density and impenetrability to liquid which though insufficient to hold back liquid if discharged at atmospheric pressure, will, however, be greater than the frictional resistance which will be encountered by the by-passed solvent in its passage through the less-compact solid material in the extraction unit and thus to permit the by-passed solvent to move in counter-current with such

solid material and in the preferred embodiment of my invention, I maintain given hydrostatic pressures at opposite sides of the discharge conduit 14 of the extraction unit I by connecting, at the discharge side of the discharge conduit 14, a combined material-conveyor and solvent column 15. The compressing mechanism for the exhausted material comprises, as illustrated, a perforated screw 16, mounted on a shaft 17 rotated through gears 17', 17" by a motor 18, and turning in the conduit 14. The said screw 16 has its end projecting into an extension conduit 14' having, at its outer end, a spring-pressed valve 14" and projecting into an enclosed delivery box M for the conveyor 15, said delivery box M having, at its lower end, an opening M' which communicates with the conveyor 15 through a horizontal portion 15' which in turn connects through the elbow portion 15" with a vertical portion 15" which extends upwardly a sufficient distance to contain a column of solvent having a liquid level F' similar to the liquid level F in the extraction tank 1, and to convey exhausted or extracted material above said level.

This conveyor 15 may be of any suitable or conventional type, but will preferably comprise an elevating conveyor-channel or ascending leg, in which solid material is adapted to be elevated by suitable members 15^a while moving upwardly and a return channel 15^b or descending leg for enclosure of the elements 15^a while descending or moving downwardly. In accordance with my invention, said descending leg 15^b is utilized as a container for solvent and provides, when filled with solvent, a solvent column providing an equalizing hydrostatic pressure to counteract the hydrostatic pressure in the unit and also a supply leg for feeding solvent to the extractor unit at such equalized pressure. In accordance with the preferred form of my invention illustrated in Figs. 1 and 2, I preferably utilize a chain conveyor having a series of carrier members 15^c provided with projecting forked portions 15^d and adapted to carry the exhausted material en masse through the elevating channel 15^c and to provide a partition 16 separating the ascending and descending channels or flights, and, as aforesaid, the descending channel is utilized to provide a solvent reservoir or hydrostatic head for the dual purposes of equalizing pressure at the discharge end of the extraction unit and of providing a supply of solvent to be by-passed therefrom to the lower end of the extraction unit.

In accordance with my said invention, the conveyor extends above the common liquid level in the extraction unit and conveyor leg, to a discharge outlet conduit 17' and solvent is supplied to the said descending leg or channel of such conveyor above said liquid level at 18, thus forming said hydrostatic head or column which communicates pressure through the delivery box M to the discharge side of the discharge conduit 14.

In accordance with the preferred form of my invention illustrated, I also treat the extracted material in the conveyor by causing the fresh solvent to percolate therethrough at or adjacent to the final discharge 17' for such extracted material. The solvent thus percolated through such material is also caused to drain into the solvent column in the descending conveyor leg. To provide for such percolating and draining of solvent, I provide the upper part of the conveyor above the solvent level F' with a perforated partition 16^a continu-

ous with the partition 16. Thus fresh solvent supplied at 18 will percolate the upwardly moving solid material from B to R, which comprises a zone from said solvent inlet to the liquid level

5 F' and above said percolating zone liquid will drain from said material through said perforated partition, thus forming a draining zone from R to A which includes the area between the solvent inlet and the material outlet.

10 In accordance with the preferred form of my invention, I by-pass, through pipes 10' and S from the solvent column to the bottom of the extraction tank, a supply of extracting liquid, and in order to maintain the solvent column at proper

15 level this by-passed supply should, at all times, be substantially equal to the supply of solvent to the said solvent column so that a continuous supply will enable continuous counter-current extraction and also that equalized pressure will always be 20 maintained at opposite sides of said discharge conduit.

25 To have counter-current extraction it is necessary that the solvent flow upwardly through the extraction column or tank 1. To have that upward flowing, it would, conventionally, be necessary to provide a difference of level in the empty leg of the conveyor great enough to overcome the resistance presented by the material positioned between the discs of the extractor from the end 30 30 E of the extraction section to the liquid level F. Such difference of level would require unusual length of the conveyor. To avoid this, I utilize pumps as hereinafter specified.

35 In the preferred form of my invention solvent is supplied to the column by a pump P above the liquid level, and the by-pass conduit which extends from the bottom of the solvent column to the bottom of the extraction unit is provided with a pump P' of a capacity substantially equal to the 40 solvent supply pump P.

45 It will be understood that in view of the maintenance of the substantially equalized pressure at opposite sides of the discharge outlet for the extraction unit, it will be unnecessary to provide, at such discharge outlet, a plug of such high density as would hold back liquid when discharging at atmospheric pressure, but it will be necessary only to provide, in such discharge conduit, a plug of a density sufficient to prevent the by-passed solvent at 10 from at once passing downwardly through the discharge conduit, and it will be understood that I provide, adjacent to the discharge conduit, a zone of compressed exhausted material of a density only sufficient to prevent 50 the passage of by-passed solvent directly through the discharge conduit or to provide a compressed mass having a resistance to solvent greater than the resistance which will be encountered by the solvent in its passage upwardly through the extraction unit to the miscella outlet. As such compressed mass or plug is formed in the outlet conduit, the supply of solvent by-passed through the by-pass conduits will be caused to pass upwardly through the raw solid material in the extraction 55 tank or unit, and during such passage will extract oil or fat from raw material, being progressively enriched during its passage till it reaches a strainer 20 and the miscella outlet conduits 21.

60 In Fig. 6, I have shown a modified form of my conveyor which is, in all respects, similar to the construction shown in Figs. 1 and 2, except that instead of the closely-spaced projecting fork-shaped carriers, I provide perforated partition conveyor members which operate in a manner 65 substantially similar to that which is hereinabove

described as to Figs. 1 to 5 except that the perforated solid partitions carry the solid material instead of projecting forked elements hereinabove specified.

70 In Fig. 1, I have shown a gravity feed tank T as an alternate form of solvent supply. This tank is, as shown, connected by a pipe t with the solvent inlet conduit 18', there being provided in the pipe t between the tank T and the inlet conduit 18' a valve t' to permit cutting in or off the supply 10 from the tank T. I also preferably provide between the pump P and the inlet conduit 18' a valve p so as to enable cutting off the solvent supply from the pump when the supply from the tank is being employed.

75 In Fig. 7 I have shown a modified form of my apparatus in which the conveyor 15 has, at its upper end, an inclined portion 15^x in which the solvent-percolating or washing zone and draining zone are positioned in a construction somewhat differing from that shown in Fig. 1. In this construction, a partition 16^b, similar to the construction shown in Fig. 1, is provided above the solvent-level line S^L with a partly vertical and partly inclined perforated partition 16^b, and solvent is supplied to conveyor leg 15^y through a supply pipe 18^a having inlets 18^b, 18^c. Obviously, when the partition 16^b is perforated the solvent passing into the leg 15^y will pass through the perforations in said partition and percolate or wash through the 80 upwardly moving solid material in leg 15^y. I also preferably provide in the embodiment shown in Fig. 7, a solvent-collecting compartment or solvent-collector C in the form of an inclined pan or jacket which is mounted on the outer surface 85 of the conveyor leg 15^x and has a perforated wall C' so that a considerable part of the solvent, after washing through the solid material moving upwardly in the ascending conveyor leg 15^y, will pass or drain through the perforated wall C' into 90 the collector C which is connected, at its lower end, with a conduit C² communicating at C³ with the descending leg of the conveyor 15. It will be seen from the above, that the solid material which is being conveyed upwardly through the inclined portion of the conveyor to the outlet 17^x will be more thoroughly washed with the solvent supply than in the case of the vertical construction shown in Fig. 1. In other respects however, this construction is similar to that shown in 95 Fig. 1.

100 In Fig. 8 I have shown still another form of my apparatus which is similar to and but slightly modified from the construction shown in Fig. 7. In this form of conveyor the upper portion is inclined further toward the horizontal than the construction shown in Fig. 7; also the perforated partition 16^c is cut away or eliminated at the turn or elbow between the vertical and inclined sections of the conveyor so as to permit a more free passage 105 of solvent through the two legs of the conveyor; furthermore, the supply pipe 18^a is provided with a series of three inlets instead of two. The solvent-collector C is mounted over a perforated wall c' and this and other parts of the apparatus is 110 substantially similar in all respects to the apparatus shown in Fig. 7. This solvent-collector also has a similar conduit C² communicating at C³ with the descending leg of the conveyor.

115 In Fig. 9 I have shown still another modified form of conveyor in which ascending and descending vertical legs are separated from each other and connected by horizontal legs to form a substantially rectangular conveyor structure. Conveyors of this type are in commercial use and 120

it will, therefore, be unnecessary to describe the method of supporting the same, it being sufficient to state that the conveyor elements are suitably driven, as for example by a suitably driven gear G to carry material from a horizontal leg up through an ascending vertical leg and thence through an elevated horizontal leg to an outlet suitably positioned therein. In this embodiment, the extractor unit is in all respects similar to the construction shown in Fig. 1. However, the delivery box M', which is in all respects similar to the box M of Fig. 1, delivers directly to a horizontally-disposed leg portion 115^a of the rectangular conveyor 115 shown in this figure, and solid material is conveyed through said portion 115^a and thence up through the ascending leg 115^a into and through a washing zone 115^b, a draining zone 115^c and thence through a horizontal elevated portion to an outlet 115^d from which the material may be sent to a suitable drier not shown. This construction is also preferably provided with a solvent collector C⁴ which is preferably disposed at one side of a perforated wall section 115^e in the ascending leg 115^a. The lower end of this collector is similarly connected with a solvent conduit C⁵ communicating at C⁶ with a descending leg 115^f of the conveyor, it being understood that in this construction also, the ascending and descending legs 115^a, 115^f of the conveyor will be filled with solvent up to the solvent-level line S^L. In this construction also, I have shown a by-pass solvent-conduit or pipe connecting the descending leg with the extractor unit, and as illustrated pipes 10^a, 10^b and a pump P^a are employed for this purpose. In other respects the device is similar to that shown in Fig. 1. Having described my invention, I claim:

1. A method for continuous counter-current solvent extraction of solid materials consisting in providing an extraction column filled with solid material, continuously feeding raw solid material through one end, passing solid material through said column in a substantially vertical direction, continuously compressing a mass of solid material adjacent to the discharge end, equalizing the hydrostatic pressure on opposite sides of said compressed mass by connecting, at said discharge end, a column of solvent, and continuously discharging said compressed material through said solvent column, and feeding solvent above said compressed mass from said column of solvent to the bottom of said extraction column in counter-current with said solid material.

2. A method for continuous counter-current solvent extraction of solid materials consisting in providing an extraction column filled with solid material, continuously feeding raw solid material through one end, passing solid material through said column in a substantially vertical direction, continuously compressing a mass of solid material adjacent to the discharge end, equalizing the hydrostatic pressure on opposite sides of said compressed mass by connecting, at said discharge end, a column of solvent, continuously discharging said compressed material through said solvent column feeding solvent above said compressed mass from said column of solvent to the bottom of said extraction column in counter-current with said solid material, and conveying said discharged material above the liquid level in said solvent column.

3. A method for continuous counter-current solvent extraction of solid materials consisting in providing an extraction column filled with solid material, continuously feeding raw solid material

through one end, passing solid material through said column in a substantially vertical direction, continuously compressing a mass of solid material adjacent to the discharge end, equalizing the hydrostatic pressure on opposite sides of said compressed mass by connecting, at said discharge end, a column of solvent, continuously discharging said compressed material through said solvent column, feeding solvent above said compressed mass from said column of solvent to the bottom of said extraction column in counter-current with said solid material, conveying said discharged material above the liquid level in said solvent column, supplying fresh solvent to said solvent column and percolating said discharged material with said fresh solvent.

4. Apparatus for continuous counter-current solvent extraction of solid materials comprising an extraction tank having, at one end, a feeding inlet for raw solid material and at the other end a discharge conduit for exhausted solid material, means within said tank adjacent to the discharge end thereof for compressing a mass of solid material, a combined material conveyor and solvent column connected with the discharge end of said discharge conduit to equalize hydrostatic pressure at opposite sides of said compressed mass and convey solid material through said solvent column, means for supplying liquid solvent to said solvent column, and a by-pass conduit connecting the combined material conveyor and liquid column with the bottom of said extraction tank at a point between the said compressed mass and the feeding inlet for solid material of the extraction tank.

5. Apparatus for continuous counter-current solvent extraction of solid materials comprising an extraction tank having, at one end a feeding inlet for raw solid material and at the other end a discharge conduit for exhausted solid material, means within said tank adjacent to the discharge end thereof for compressing a mass of solid material, a combined material conveyor and solvent column connected with the discharge end of said discharge conduit to equalize hydrostatic pressure at opposite sides of said compressed mass and convey solid material through said solvent column, means for supplying liquid solvent to said solvent column, and a by-pass conduit connecting the combined material conveyor and liquid column with the bottom of said extraction tank, said combined conveyor and solvent column having conveyor and solvent-containing legs separated by a partition and provided, at its upper end, with a solvent inlet through the conveyor leg, said partition being perforated at its upper end to permit passage of solvent from one leg to the other.

6. Apparatus for continuous counter-current solvent extraction of solid materials comprising an extraction tank having, at one end, a feeding inlet for raw solid material and at the other end a discharge conduit for exhausted solid material, means within said tank adjacent to the discharge end thereof for compressing a mass of solid material, a combined material conveyor and solvent column connected with the discharge end of said discharge conduit to equalize hydrostatic pressure at opposite sides of said compressed mass and convey solid material through said solvent column, means for supplying liquid solvent to said solvent column, and a by-pass conduit connecting the combined material conveyor and liquid column with the bottom of said extraction tank, said combined conveyor and solvent column having

conveyor and solvent-containing legs separated by a partition and provided, at its upper end, with a solvent inlet through the conveyor leg, said partition being perforated at its upper end to permit 5 passage of solvent from one leg to the other, and said perforated partition having an upward extension above the solvent inlet to permit draining of percolated solvent.

7. Apparatus for continuous counter-current 10 solvent extraction of solid materials comprising an extraction tank having, at one end, a feeding inlet for raw solid material and at the other end a discharge conduit for exhausted solid material, means, within said tank adjacent to the discharge 15 end thereof, for compressing a mass of solid ma-

terial, a combined material conveyor and solvent column having a washing and percolating section and connected with the discharge end of said discharge conduit to equalize hydrostatic pressure at opposite sides of said compressed mass and convey 5 solid material through said solvent column, and a by-pass conduit between said solvent column at said washing and percolating section and said extraction tank above said compressing means at a point between the compressed mass and the 10 feeding inlet whereby a supply of solvent percolating from said washing and percolating section is passed through said tank in counter-current with said solid material.

MICHELE BONOTTO. 15
